US0D1043896S

(12) **United States Design Patent** (10) **Patent No.:** **US D1,043,896 S**
(45) **Date of Patent:** **** Sep. 24, 2024**

(54) **PROJECTILE**

(71) Applicant: **G9 Holdings, LLC**, Lakewood, CO
(US)

(72) Inventor: **Joshua Mahnke**, Post Falls, ID (US)

(73) Assignee: **G9 HOLDINGS, LLC**, Lakewood, CO
(US)

(**) Term: **15 Years**

(21) Appl. No.: **29/859,100**

(22) Filed: **Nov. 7, 2022**

Related U.S. Application Data

(60) Continuation of application No. 17/354,347, filed on Jun. 22, 2021, now Pat. No. 11,808,550, which is a division of application No. 16/707,820, filed on Dec. 9, 2019, now Pat. No. 11,041,703, which is a division of application No. 15/406,781, filed on Jan. 16, 2017, now Pat. No. 10,502,536.
